UNITED STATES PATENT OFFICE.

ROBERT LEE EVANS, OF SCOTTSBOROUGH, ALABAMA.

CAR-COUPLING.

SPECIFICATION forming part of Letters Patent No. 400,068, dated March 26, 1889.

Application filed August 7, 1888. Serial No. 282,187. (No model.).

To all whom it may concern:

Be it known that I, ROBERT LEE EVANS, of 5
Scottsborough, in the county of Jackson and
State of Alabama, have invented a new and
useful Improvement in Car-Couplings, of
which the following is a specification.

My invention relates to car-couplings, and
has for its object to provide a simple and effi- 10
cient means for the coupling of cars; and it
consists in the peculiar construction and com- 15
bination of parts, as will be hereinafter fully
described, and pointed out in the claims.

In the drawings, Figure 1 is a perspective
view of my improvement as applied to a car. 15
Fig. 2 is a side elevation, partly in section, of
the same as applied to two adjoining cars.
Fig. 3 is a detail view of the pin-holder, and
Fig. 4 is a view of one of the links.

To the end A of the car-body is applied the
draw-head B, of usual construction, which is 20
provided with the pin-openings b b', through
which operates the pin C. The pin C is formed
of the lower portion, c, which operates in the
draw-head, and with the upper extended 25
portion, c'. The upper end of the pin C ex-
tends through and is guided in a slot, d, of a
bracket, D, extended from the car-body, and
about midway its length it is provided with a
fixed collar, c².

Mounted upon the extension c' of the link,
and resting at its lower end upon the collar
c², is a coiled spring, E, the upper portion, e,
of which extends up to and is held in place by
the bracket D, as shown. In practical use it 35
is preferred to place a loose collar, F, upon the
pin C, which rests against the lower edge of
the bracket D, and thereby serves to assist
in steadyng the spring and pin when the pin
is moved upwardly.

In brackets G G on the ends of the car is
journaled a transverse shaft, H, provided at
each end with hand-wheels I for turning it. 40
Attached centrally to said shaft is one end of
a chain, J, the other end of which is secured
to the upper end of the pin C, as at j.

In the front face of the draw-head, and to
each side of the mouth a, are fromed grooves
L L, in which is pivoted the pin-holder M. 45
The pin-holder M consists of a Ω -shaped bar
pivoted at m m in the grooves L L, as stated,
and has its lower extensions or arms, m' m',

arranged to fit in the extensions l l of the
grooves L. The upper portion, m², is extended
upwardly and inwardly over the draw-head
and extends approximately in the path of the
movement of the pin, as shown. The upper 55
end, m², of the holder is arranged to drop under
the collar c² of the pin when the same is
raised, and to effectively cause the said upper
end of the holder to automatically drop under 60
said collar. Springs N N are seated in recesses
n n in the grooves L L in the draw-heads,
which springs normally press the arms m m
of the holder outwardly, and thereby force
the upper yoke portion, m², inwardly. By 65
this construction it will be seen that when it is
desired to couple the car to another the shaft
G is turned and the chain J is wound there-
on, which will pull the pin C up and contract
the spring. When the pin has been raised 70
to a height sufficient for the lower end of the
pin to rise out of the recess B' of the draw-
head, the collar c will have passed the edge
m² of the holder M, which will drop under said
catch, and thereby hold the pin in its raised 75
position. Now, as the draw-head of the adja-
cent car approaches, its link will enter the re-
cess B', and when the draw-heads close up the
projecting arms m' m' of the support will be
struck, the upper edge, m², will be released 80
from the collar c', the tension of the spring
thereby released, the pin C forced down
through the link, and thereby coupling the
car. The link is formed of a bar, O, having
beveled upturned ends o, and provided with 85
elongated slots o' at each end. When it is
desired to couple cars of different heights,
links of the form shown in Fig. 4 are used,
which consist of forming the link above de-
scribed with the central portion, o², bent up- 90
wardly, as shown.

From the foregoing description, taken in
connection with the drawings, the operation
of my invention will be readily understood.

Having thus described my invention, what 95
I claim as new is—

1. In a car-coupler, the combination, with
the draw-head B, the pin C, having a fixed col-
lar, c², and means, substantially as described,
for raising the pin, of a Ω -shaped pin-holder 100
adapted to engage the collar c² of the pin C,
said holder pivoted to the draw-head and pro-

vided with extending arms $m m$, adapted to be struck by the draw-head of an approaching car, substantially as and for the purposes described.

- 5 2. In a car-coupler, the combination, with the draw-head B, provided with grooves L L and recesses n, and the Ω -shaped pin-holder pivoted in the grooves L, the upper portion, m^2 , thereof extending upwardly and rearwardly over the draw-head, the lower extending arms, $m m$, fitting the grooves L L, and springs N, seated in the recesses n n and adapted to normally throw the arms $m m$ outwardly, of the coupling-pin C, said pin consisting of the lower portion, c , the upper extended portion, c' , provided with a fixed collar, c^2 , and means, substantially as described, for raising the link, whereby the collar is adapted to be engaged

by the holder M, substantially as and for the purposes described.

3. In a car-coupler, the combination, with transverse shaft G, provided with operating-wheels H, and the bracket D, having an elongated slot, d , of the pin C, its upper end passing through slot d in the bracket D and connected with the shaft G, and provided with a fixed collar, c^2 , the spring E, mounted on said pin and disposed between the collar c^2 and the bracket D, and the Ω -shaped supporter M, pivoted on the draw-head adapted to hold said pin in its elevated position, all arranged substantially as and for the purpose specified.

ROBERT LEE EVANS.
